MEANS FOR CONTROLLING AN ENGINE-DRIVEN GAS COMPRESSOR

Guy Baron Boyce, Shenstone, England, assignor to The Hydrovane Compressor Company Limited, Walsall, England

Application October 25, 1954, Serial No. 464,463

Claims priority, application Great Britain

November 4, 1953

4 Claims. (Cl. 230—9)

This invention relates to means for controlling the action of an engine-driven air or other gas compressor, the engine being of the internal combustion type, and the compressor being of the type comprising a rotor mounted in a working chamber and provided with slideable radial vanes, the sealing of the vanes being effected by oil which is supplied to the working chamber under pressure from a separator which receives oil-laden air from the compressor.

The object of the invention is to provide in a convenient form an engine (or engine and compressor) control means responsive to the pressure of oil received from the separator.

A control means in accordance with the invention includes a spring-loaded throttle adapted to control the flow of oil from the separator to an oil accumulating chamber, and an engine controlling mechanism responsive to the pressure of the oil received from the said chamber.

The invention also comprises the combination with the means specified in the previous paragraph of a valve operable by pressure of the oil received from the said chamber for controlling the admission of air to the compressor.

A convenient embodiment of the invention will be described, by way of example, with particular reference to the accompanying drawings in which:

Figure 1 is a diagrammatic view showing the interrelationship and mode of interconnection of the parts, some of which are illustrated in detail in the other figures.

Figure 2 is a sectional view through the body part containing the throttle and fluid operated valve controlling the air admission aperture of the compressor.

Figure 3 is a sectional view of the mechanism for varying the setting of the governor.

Figure 4 is a sectional view of mechanism whereby air pressure can be utilised for actuating the mechanism seen in Figure 3, and,

Figure 5 is a device for permitting the control to be effected directly upon the engine throttle or fuel supply instead of upon the engine governor.

Figure 6 is a diagram illustrating the manner in which the device shown in Figure 5 is connected to the associated parts.

In Figure 1, 6 represents the internal combustion engine which drives a compressor 7 of known kind, having an eccentrically mounted rotor with slideable radial vanes in a cylindrical working chamber, the sealing of the vanes being effected by oil which is supplied to the working chamber under pressure from a separator 8. The admission of air to the compressor 7 is by way of a conduit 9 from an air inlet 10 controlled by a valve 11. The separator 8 separates the admixture of air and oil delivered by the compressor 7 and delivers the air under pressure to the pipe 12 which is connected to the associated air distributing system. The compressor, separator and other parts above described may be similar to those illustrated in Figures 3, 3a and 3b of U. S. Patent No. 2,722,395 in which the separator has the form of an oil reservoir into which oil-laden air from the compressor is discharged. The oil from the separator, which is at

2

the same pressure as the air, is connected by means of the pipe 13 to a port 14 in a body part 15 having a bore 16 (Figure 2) containing a cylindrical and spring loaded throttle 17. The throttle 17 controls the flow of oil to an annular chamber herein referred to as the oil accumulating chamber 18, formed in the bore 16. The oil accumulating chamber 18 is connected by a passage 19 and pipe 20 to a mechanism 21 to be actuated by pressure of the oil and to be referred to hereinafter. Another passage 22 in the body part 15 leads from a circumferential groove 23 in the bore 16 to the compressor 7, the connection between this passage and the compressor being indicated by 22a in Figure 1. In the part of the throttle 17 which forms the inner peripheral boundary of the oil-accumulating chamber 18 is formed a shallow groove 24 by which oil can seep from the said chamber to the groove 23 and thence to the compressor.

The throttle 17 is so formed that a small variation of the oil pressure acting on it is accompanied by a relatively large variation of the pressure in the oil-accumulating chamber 18, the spring 25 determining at what pressure in the separator 7 oil is admitted to the oil accumulating chamber.

The mechanism 21 to be actuated by the oil pressure serves to vary the setting of the engine governor 26, which latter controls the throttle 27 in the air-intake manifold of the engine, or the supply of liquid fuel. In one example the mechanism 21 (seen in Figure 3) comprises a hollow body part 28 having an inlet port 29 to which the pipe 20 is connected. The body part 28 is also provided with a restricted bleed orifice 28' leading to atmosphere via port 28'' and in which is contained a compressible spring loaded elastic metal bellows 30. One end of the bellows 30 is fixed, and the closed movable end 30a acts on a slideable rod 31 which is disposed within the bellows and is connected to a lever 32 pivotally mounted on the said body part, the lever 32 being connected by a link 33 to the governor 26. The pivot 34 of the lever 32 is carried on a spring-loaded stem 35 in the body part, so that when the governor is moved to one of its limit positions any additional movement of the bellows 30 is accommodated by displacement of the pivot axis.

It will be understood that in an apparatus which includes an engine, a compressor, and an oil separator as above mentioned, the oil in the separator 8 is subject to the pressure of the air discharged from the compressor 7 to the associated air distributing system (the term "air" being herein intended to include any gas). This pressure is at its maximum when no air is being drawn from the system, and at other times it varies with the rate of demand for air.

In the arrangement above described oil from the separator 8 is returned to the compressor 7 through the throttle 17, and the pressure of the oil retained in the oil-accumulating chamber 18 varies with the demand for air. When the demand is zero, the oil pressure acting on the bellows 30 causes the governor 26 to reduce the speed of the engine 6 to the idling speed. It may be, however, that this alone is insufficient to reduce to the desired relatively low amount the pressure to which the air is compressed by the compressor 7.

To meet this requirement the accumulating chamber 18 is in communication, through a passage 36 with the region 37 in a bore parallel with the bore 16. In the said bore is a fixed bush 38 in which is slideable the hollow stem 39 of an air-inflow controlling member. This member has a head 39a upon which the oil pressure acts and is spring loaded in opposition to the oil pressure by a spring 40 interposed between a foot 41 on the said member and the fixed bush 38.

In the hollow stem 39 is freely slideable the stem 11a

of the valve 11 which controls the admission of air through the inlet 10 to the passage 42, which is connected by the pipe 9 to the compressor. Movement of the head 39a to the right as viewed in the drawing, due to an increase in oil pressure in the oil accumulating chamber, closes or partially closes the valve 11 upon its seat, due to the abutment of the head 39a with a shoulder on the valve 11. Consequently when an excess air pressure persists at idling speed the load on the compressor is further reduced by restriction or interruption of the air supply to the compressor.

The left hand end of the bore 16 is in communication through passage 43 and an axial bore 44 in the valve 11 with atmosphere to prevent hunting of the throttle 17 when the compressor is in action. When the compressor is at rest and the associated system is under pressure, loss of this pressure by leakage of oil past the throttle 17 and through passage 43 and bore 44 is prevented by a non-return valve 45.

Although in Figure 1 the compressor 7, separator 8, and body part 15 are shown for simplicity as separate units connected by pipes, in practice they are all contained within a common casing.

In the foregoing arrangement the bellows 30 is actuated directly by pressure of the oil. But in some conditions this is undesirable, for in the event of fracture of the pipe 20 leading to the bellows, inconvenient loss of oil would result. To obviate this compressed air may be used for actuating the bellows 30, it being of less consequence to lose air than oil in the event of fracture of the pipe connected to the bellows. In an alternative arrangement, in conjunction with the above described bellows-actuating means the device illustrated in Figure 4 therefore, may be employed.

The passage 19 may be connected by the pipe 20 to the inlet 46 of a cylinder 47 having an outlet 48 for compressed air, which is connected to the inlet 29 of the device seen in Figure 3. In the cylinder 47 is a spring loaded piston 49 which acts upon a slideable throttle 50, which serves to open a spring-loaded air valve 51, controlling the admission of compressed air from an inlet 52. The throttle 50 consists of a tapered plug slideable in a cylindrical bore; so as to form a variable orifice for admitting the compressed air to the underside of the piston 49 and thence to the outlet 48. The oil entering the cylinder above the piston from the inlet 46 passes through a restricted orifice in a spring loaded valve 53. If pressure is reduced at the inlet 46 oil can flow back through the inlet relatively quickly by lifting this valve off its seat.

A variable oil pressure acting on the piston 49 consequently results in a correspondingly varying air pressure for actuating the bellows 30. Thus, downward movement of the piston 49 is accompanied by compression of the air in the cylinder 47 at the underside of the piston for actuating the bellows, and causes the throttle 50 to open the valve 51 for permitting access of compressed air from the inlet 52 to the cylinder after the throttle has been moved downwards to a predetermined extent. Upon the piston 49 being subsequently moved upwards, due to decrease of the oil pressure acting thereon, the throttle 50 moves towards its closed position so that the upward movement of the piston causes the air pressure in the cylinder 47, and acting on the bellows, to be reduced due to the escape of air through bleed orifice 28', the valve 51 closing if the upward movement of the piston is sufficient.

In Figures 5 and 6 is illustrated a compensating device whereby the lever 32 (Figure 3) may be connected to the throttle 27 or fuel controlling device of the engine 6 without using a governor. It will be understood that, if the lever 32 were connected directly to the throttle or fuel controlling device 27 without some form of compensation, then when the engine speed were reduced in response to an increase of pressure in the compressor,

and the pressure were again to rise in the compressor thus causing the inlet control valve 11 to close, the resulting removal of load upon the engine would cause the engine speed to increase.

The device illustrated in Figures 5 and 6 is adapted to be interposed in the link 33 connecting the lever 32 with the engine throttle or fuel controlling lever. The link 33 is formed in two parts, one part being connected to a housing 54 containing a diaphragm 55, and the other part being connected to a plunger 56 connected to the diaphragm 55 and slideable in a cylindrical portion of the housing 54. The interior of the housing is in communication through a port 57 and a passageway 59 with the air intake to the compressor 7 on the down-stream side of the valve 11. The arrangement is such that a reduced pressure in the air intake will cause a relative axial movement of the two parts of the link 33 against the action of a spring 58 to shorten the effective length of the link 33, and thus close the engine throttle or reduce the fuel supply to the engine still further.

Having thus described my invention what I claim as new and desire to secure by Letters Patent is:

1. Means for controlling the action of an engine-driven air or other gas compressor of the kind in which a rotor mounted in a working chamber is provided with radial vanes which are sealable by oil supplied under pressure to the working chamber from a separator receiving oil-laden air from the compressor, comprising in combination an oil accumulating chamber, a passage for conducting oil under pressure from the separator to the accumulating chamber, a spring-loaded throttle arranged in said passage for controlling oil flow to the accumulating chamber, an engine controlling mechanism having an actuating member responsive to fluid pressure, and means interconnecting said accumulating chamber and said actuating member for subjecting the actuating member to a fluid pressure which varies with the oil pressure in the accumulating chamber.

2. Means according to claim 1 and having in combination therewith a valve for controlling the admission of air to the compressor, actuating means through the medium of which the valve is operable by oil pressure, and a passageway connecting said accumulating chamber and said actuating means for conducting oil under pressure from the accumulating chamber to the valve actuating means.

3. Means according to claim 1 and having in combination therewith a cylinder, a spring-loaded piston slideable in the cylinder, a passageway interconnecting the accumulating chamber and the cylinder to conduct oil under pressure from the accumulating chamber to the cylinder at one side of the piston for moving the latter against its spring loading, a second passageway interconnecting the cylinder and the engine-controlling mechanism for conducting air under pressure from the cylinder at the other side of the piston to the actuating member of the engine-controlling mechanism, and a valve operable by the piston for controlling the flow of the air under pressure to the part of the cylinder communicating with the second passageway, so that the air pressure acting on the actuating member varies with the pressure of the oil in the accumulating chamber.

4. Means according to claim 1 and having in combination with the engine-controlling mechanism, a two-part link through which the controlling action of the said mechanism is effected, and a compensating device interconnecting the link parts, the said device having components relatively movable in response to air pressure for varying the effective length of the link.
